UNITED STATES PATENT OFFICE.

GEORGE EDWARD PRENTICE, OF BERLIN, CONNECTICUT, ASSIGNOR TO G. E. PRENTICE MANUFACTURING COMPANY, OF NEW BRITAIN, CONNECTICUT, A CORPORATION OF CONNECTICUT.

KEY CASE.

Application filed August 22, 1925. Serial No. 51,837.

To all whom it may concern:

Be it known that I, GEORGE E. PRENTICE, a citizen of the United States, residing at Berlin, in the county of Hartford and State 5 of Connecticut, have invented certain new and useful Improvements in Key Cases, of which the following is a specification.

My invention relates to improvements in key cases of the form in which a set of 10 hanger supports and hook-like clips for receiving keys are incorporated in a case of leather or the like and the object of my improvement is to provide intermediate the leather case and a set of hanger supports 15 like those shown and described in the application filed by Robert C. Legat March 23, 1925, Serial No. 17,694, a supporting structure that is secured to the leather case and has individual loops for engaging with the 20 openings in the hanger supports whereby a substantially swivel connection is provided and thus a second flexible connection, in addition to the ball and socket joint of the hanger support, will be incorporated between the leather case and the key-receiving 25 clip.

In the accompanying drawing:—

Figure 1 is a front elevation of part of a 30 key case in the open position showing a supporting structure embodying my invention and a set of hanger supports and hangers or key receiving clips that correspond to one form that is shown and described in the application above referred to.

Figure 2 is an edge view of the supporting structure and the parts supported thereby.

Figure 3 is a plan view of the blank for the supporting structure.

Figure 4 is a plan view of the blank for the hanger support.

Figure 5 is a sectional view taken through the ball and socket joint.

My improved key case comprises a casing 45 proper 10 of leather that is adapted to be folded over to enclose the key supporting devices and the keys in the usual manner, the keys being engaged individually with hook-like clips or hangers 11.

The hangers 11 are connected to hanger supports 12 by means of a ball and socket joint 13, all of which are shown and de-

scribed in the application above referred to. Thus, briefly, the hanger 11 has a shank 14 and the upper end portion 15 of said shank 55 14 is curled over into somewhat of a ball shape. The shank 14 is entered through an opening in the lower end of the ball portion 17 of the hanger support 12.

The hanger support 12 is made of sheet 60 metal and the ball portion 17 is formed from the plate-like middle portion of the blank that is substantially of square shape and is defined by the side edges 18. Short and reduced connecting necks 19 extend outwardly 65 on opposite sides from the ends of a diagonal are brought into face to face contact or into close relation so as to cooperate to provide a supporting shank or the like for the ball 17. The necks 19 merge with enlarged 70 ears 20 that have openings 21 in registration for receiving means that are provided for holding the hanger supports 12.

In the present instance said means comprise for each hanger support 12 a loop 22 75 that is positioned in a plane that is in perpendicular relation to the opposed face of the back 23 of the leather casing 10. Thus, with the hanger supports 12 and the keys in the pendant position and housed within the 80 casing 10 the supporting ears 20 are substantially in parallelism with the back 23 and the movements permitted the hanger supports are the substantial equivalent to such as are provided by a swivel connection. 85

Such movement consist of a combination of a swinging in a perpendicular plane along the structure of the loop 22, which in extent is considerably more than one hundred and eighty degrees, and a lateral pivotal movement of substantially one hundred and eighty degrees. 90

As shown, the loops 22 are in the form of individual fingers, eight in number, that are connected along the top edge 24 of a 95 plate or body 25, the latter being secured to the casing back 23 by a set of eyelet rivets 26.

The ball and socket joint facilitates the turning of the individual keys when engaged with the lock and also the nesting of the keys snugly within the casing 10. 100

The swivel joint 27, provided by the ears 20 and the loops 22, provides for flexibility

2
generally and in particular for swinging the hangers and keys back and forth between the outside position and the inner position, and facilitates the selection of a particular 5 key for use.

It will be understood that no claim is made in this application to the structure of the hanger support and hanger per se, the same being claimed in the copending 10 application of R. C. Legat, Serial No. 17,694. The present case is directed to the combination of the structure claimed in said copending application with an improved supporting plate for attaching the device to a key 15 case. It will be observed that there is a clear coaction, and, therefore, a true combination between these structures, since the curled fingers of the supporting plate permit of a universal movement at the supporting plate and the plate element affords a 20 backing for the swivel joint when the keys are positioned within the case.

I claim as my invention:—

In combination, a supporting plate for attachment to a key case, having at one edge 25 a plurality of spaced fingers bent back into contact with the plate and forming loops, a plurality of hanger supports each attached to one of said fingers for free swinging movement thereon, and each having a pendant portion in the form of a substantially 30 hollow structure that is provided with an opening at the lower end, a hanger for receiving a key having a shank of wire that is projected through said opening so that 35 the free end portion is housed within said structure, and said free end portion being curled upon itself in the plane of the shank without diminishing the cross sectional area thereof to provide an operative fit within 40 said structure for cooperating therewith as a swivel connection.

GEORGE EDWARD PRENTICE.
